BY *William J. Jackson*
ATTORNEY.

UNITED STATES PATENT OFFICE.

WALTER STEEL, OF PHILADELPHIA, PENNSYLVANIA.

DESIGN FOR A PAPER-WRAPPED CANDY KNOWN AS BONNY BONNET POPS.

59,692.

Specification for Design.

Patented Nov. 15, 1921.

Application filed August 16, 1921. Serial No. 492,843. Term of patent 14 years.

To all whom it may concern:

Be it known that I, WALTER STEEL, a citizen of the United States, residing at Philadelphia, in the county of Philadelphia and State of Pennsylvania, have invented a new, original, and ornamental Design for Paper-Wrapped Candy Known as Bonny Bonnet Pops, of which the following is a specification, reference being had to the accompanying drawing, forming part thereof, in which—

Figure 1, is a view in front elevation of

paper-wrapped candy known as Bonny Bonnet Pops showing my new design.

Fig. 2, is a view thereof in rear elevation, and

Fig. 3, is a view thereof in side elevation.

I claim:—

The ornamental design for paper-wrapped candy known as Bonny Bonnet Pops substantially as shown.

WALTER STEEL.
